UNITED STATES PATENT OFFICE.

ARTHUR J. ROTH, OF CHICAGO, ILLINOIS, ASSIGNOR TO JAMES H. RHODES & COMPANY, OF CHICAGO, ILLINOIS, A CORPORATION OF ILLINOIS.

STEEL-WOOL-MAKING MACHINE.

Application filed June 2, 1922. Serial No. 565,297.

To all whom it may concern:

Be it known that I, ARTHUR J. ROTH, a citizen of the United States, residing at Chicago, in the county of Cook and State 5 of Illinois, have invented a certain new and useful Improvement in Steel-Wool-Making Machines, of which the following is a specification.

This invention relates to machines for 10 making what is known in the trade as steel wool by taking small shavings off from a wire or band of steel passed through the machine. While such machines have been used for a quarter of a century with a single 15 wire, no one has, prior to my earlier application, Serial No. 513,374, on which this is an improvement, been able to build a machine in which the capacity could be increased by making the same tool which shaves the wool 20 from a single wire take the wool from two or more wires at the same time.

The object of the invention is to provide 25 a machine capable of attaining this purpose, which does not occupy any more space than previous machines or cost materially more.

The invention consists in such a machine which can be easily and cheaply made, which is satisfactory in use and is not readily liable to get out of order; more particularly, the invention consists in many features and details of construction which will be hereafter more fully set forth in the specification and claims.

Referring to the drawings in which like 35 numerals designate the same parts throughout the several views:

Figure 1 is a side elevation of a complete machine illustrating this invention in its preferred form.

Figure 2 is a sectional view on line 2—2 of Figure 1, showing the drum shifting mechanism for keeping the wires in position on the table or support where the steel wool is cut.

Figure 3 is an enlarged sectional view of left hand half of Figure 1 on line 3—3 of Figure 4.

Figure 4 is a plan view of the device of Figure 3.

Figure 5 is a vertical sectional detail view on the line 5—5 of Figure 3.

Figure 6 is a detail view on the line 6—6 of Figure 1.

The wool cutting machine proper is conventionally supported by frame 10 having

end extensions 12, the whole resting on the floor 14 in the obvious manner. Carried by the frame, heretofore described, is an elongated support or table 16 having tapered downwardly extending extensions 18, approaching oppositely disposed pairs of tandem wire reeling drums 20—21 and 22—23 carried on suitable shafts.

Over table 16, as in a single wire machine, are a plurality of turret heads 24, provided with angularly disposed tool-holders 26, to each of which may be detachably secured by set screw 28 a cutting knife or chisel 30, pointed in an inclining direction toward the table, so that it engages wires passing, under the set-up shown in the drawings, from the left to right across the table 16 as viewed in Figures 1 and 3 and cuts or planes from them shavings which, when sufficiently thin and of sufficient quantity, mat into conventional commercial steel wool. The tool carrying arms 26 are adjustable angularly with reference to the surface of the table 16 by conventional set screws 32.

Mechanism not entering into this invention is conventionally provided as shown in Figure 2 whereby power from an external source communicated to a pulley 34 at a given end of the machine is transferred to the adjacent drum 21, through a shaft 36 and the reel shifting mechanism 37 which is by the use of conventional mechanism 38 and suitable gearing 39 adapted to laterally reciprocate wheel 21 to keep wire 40 passing off from the reel feeding directly to rollers 42.

Drum 20 which, as heretofore indicated, is substantially tandem with drum 21, and the table 16 is mounted on a shaft 44 parallel to shaft 36 and is driven in unison with it by any suitable means—as, for instance, the belt 46 passing over pulleys 48 and 50 on the respective shafts so that the power of pulley 34 is communicated to shaft 44. Drum 20 is provided with a shifting mechanism 52, operating synchronously with shifting mechanism 38 of drum 21 whereby the two drums 20 and 21 not only rotate in unison but shift laterally in unison to maintain the wire 40 from drum 21 and the wire 54 from drum 20 in parallelism as they pass under the roller 42 and thence over the table mechanism 18—16—18 to the drums 22 and 23.

A conventional clutch operating lever 56, 110

controlling a clutch mechanism 58, is provided adjacent to pulley mechanism 34 so that the power supplied to the mechanism from outside the device through the agency 5 of a belt mechanism 59 may be controlled in conventional manner.

The wire reeling drums 22 and 23 on the right hand end of the machine, as shown in Figure 1, are equipped with identical operating mechanism, not shown in detail, whereby the operator can by manipulating the power lever 56 at the right hand end of the machine, draw wire on drums 20 and 21 over the table and wind it up on the drums 22 10 and 23. Cutting knives 30 are shown positioned for this operation. When, however, the turrets 24 are reversed in conventional manner well understood in this art, and the drums 22 and 23 are loaded with wire, the 15 operator can manipulate power controlling lever 56 at the left hand side of the machine to cause drums 20 and 21 to pull the wires across the table from right to left, thus 20 transferring the wire from drums 22 and 23 25 to drums 20 and 21.

Table 16 is provided at proper intervals with a plurality of elongated slots 60, 62 and 64 below which are respectively mounted a corresponding number of rollers 66, 68 and 30 70, so located that only the upper circumferential portions extend through these slots as shown in Figure 1 and engage wires 40-54 placed side by side to travel in grooves 72 and 74 provided for them in the 35 respective rollers.

Pulley 66 is carried on a shaft 76 which also forms the pivotal point for a pair of parallel levers 78, carrying at their left hand ends, as viewed in Figure 3, a roller 40 42 adapted to press upon wires 40 and 54, this under the action of a hand-controlled set screw 80 located as shown in Figure 3 at the opposite ends of the levers 78 and entering the adjacent table portion 18. The 45 operator can by properly adjusting screw 80 cause roller 42 to press on wire 40 with sufficient force so that all of the slack in the wire 40 to the left of the roller 42 is taken out of it and that portion of the wire which 50 is at the right of the roller 42 is therefore retained on the table under suitable tension. Wires 40 and 54 are maintained at proper uniform tension by placing another roller 82 opposite roller 70 and adjustably positioning this latter roller on the wires 36 by the use of adjustable set screws 84 carrying springs 86 which press upon cross head 88 carrying the roller 82 in the manner made 55 entirely clear in Figure 5.

60 The tension condition of the wires 40 and 52 is also maintained by the application of an additional roller 90 to the first or left hand one of the tool-carrying arms 26, shown in Figures 1 and 3.

65 By the time the power, which in the cycle

of operation shown in the drawings is applied to the right hand wheels or drums 22 and 23, has operated to pull the parallel wires 40 and 54 coming off from the left hand drums 20 and 21 under these tension 70 rollers 42-82-90, all portions of the wires approaching and passing under the respective knives 30 are under sufficient uniform tension so that they travel under substantially the same tension over the table 16 and 75 under the knives 30 with the result that each single knife 30 cuts from each of the wires a shaving of metal ultimately going into the steel wool product and does this with the same regularity and efficiency as though 80 there were only one wire present, as in prior constructions. This is very essential because if the tool gets a chance to bite too deeply into either wire, there will be a destruction of the efficiency of the machine; 85 if a more or less serious accident does not occur.

As is well understood in the art, the practice is when substantially all of the wire has been wound off from drums 20 and 21 onto 90 drums 22 and 23 and the desired shavings have been taken therefrom by the cutting tools 30, to reverse the direction of operation of the machine and to reverse the turrets 24 and repeat the operation continuing 95 these reversals until the final remaining bodies of wire 40 and 54 are so thinned that they will no longer stand the strain of being pulled under the knives 30; the right hand end of table 16 is therefore as shown in Figure 100 105 equipped with tension rollers corresponding to those on the left hand half of the machine adapted for use when the wires are traveling from right to left through the machine.

The cutting tools 30 have to, because of the requirements of strength of material, be of a certain predetermined width and by the use of this invention two wires 40 and 54 can be passed under a given tool without increasing its size thereby in effect increasing 110 the efficiency of tools if not that of the entire machine 100%,—this without requiring any more attendants to run the machine with two wires than to run it with one wire. 115

There are several features of this invention which do not appear on the surface which are really very important in the successful manufacture of steel wool. These are principally based on the fact that when 120 wire is wound off from one drum onto another adjacent to it, the wire does not straighten but follows a curve which is determined in a large measure by the size of the wire and the closeness with which it is 125 wound. In the mechanism of this invention, advantage is taken of this fact by making the table 18-16-18 in a curve struck about a center lying below the floor on which the table rests which corresponds approximately 130

to this natural curvature of the length of wire as it comes off from one of the drums 21 and is wound onto the other drum 23. By so forming the table, the upper surface of the wire as it lies on this natural curve is more readily controlled under the cutting tools 30 than would be possible were it attempted to pass the wire over a perfectly flat table. Another feature resulting from this natural curve in the length of wire is made use of in always passing one wire 40 from drum 21 to drum 23 and the other wire 54 from drum 20 to drum 22, the two drums which thus handle each wire being equidistant apart so that the curve traveled by each wire in passing from one of its drums to the other is the same in each case. This fact results in an even cutting of the steel wool from the wires by the knives 30 which would not take place were one wire wound from drum 21 to drum 22 and the other wire wound from drum 20 to drum 23 and vice versa.

In case the device may strike the reader as simple and more or less obvious, it may be stated that the fact is: Steel wool makers using this general type of machine have, for a quarter of a century, sought to put two wires through the machine and failed until machines of the earlier mentioned application and this application were put into commercial use.

What I claim is:

1. In mechanism of the class described a support for the passage of parallel wires, a pair of wire holding drums in tandem at each end of the support adapted to pass two parallel wires over said support, a cutting tool adjacent to the support engaging the wires traveling over the support and tensioning devices on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving.

2. In mechanism of the class described, a support for the passage of parallel wires, a pair of wire holding drums in tandem at each end of the support adapted to pass two parallel wires over said support, means mounting the drums so that each wire passes from the inside drum of one pair to the outside drum of the other pair, whereby the curves of two wires between these respective drums is the same, a cutting tool adjacent to the support engaging the wires traveling over the support, and tensioning devices on the side of the cutting tool from which the wires are delivered adapted to engage said plurality of wires placed side by side and passing in engagement with the tool to sufficiently tension said wires passing the tool to simultaneously cut from each wire a steel wool shaving, means for driving said drums and automatic means laterally shifting said drums to maintain the wires parallel on the support.

so that the single tool may simultaneously cut from each wire a steel wool shaving.

3. In mechanism of the class described, a support for the passage of parallel wires curved on its working surface in an arc corresponding to the natural curvature of wires passing from coils at one end of the support to coils at its opposite end, a pair of wire holding drums in tandem at each end of the support adapted to pass two parallel wires over said support, a cutting tool adjacent to the support engaging the wires traveling over the support and tensioning devices on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving.

4. In mechanism of the class described, a support for the passage of parallel wires curved on its working surface in an arc corresponding to the natural curvature of wires passing from coils at one end of the support to coils at its opposite end, a pair of wire holding drums in tandem at each end of the support adapted to pass two parallel wires over said support, means mounting the drums so that each wire passes from the inside drum of one pair to the outside drum of the other pair, whereby the curves of two wires between these respective drums is the same, a cutting tool adjacent to the support engaging the wires traveling over the support, and tensioning devices on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving.

5. In mechanism of the class described, a support for the passage of parallel wires, a pair of wire holding drums in tandem at each end of the support adapted to pass two parallel wires over said support, a cutting tool adjacent to the support engaging the wires traveling over the support, tensioning devices on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving, means for driving said drums and automatic means laterally shifting said drums to maintain the wires parallel on the support.

6. In mechanism of the class described, a support for the passage of parallel wires, a pair of wire holding drums in tandem at

- each end of the support adapted to pass two parallel wires over said support, means mounting the drums so that each wire passes from the inside drum of one pair to the outside drum of the other pair, whereby the curves of two wires between these respective drums is the same, a cutting tool adjacent to the support engaging the wires traveling over the support, tensioning devices on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving, means for driving said drums and automatic means laterally shifting said drums to maintain the wires parallel on the support. 40
8. In mechanism of the class described, a support for the passage of parallel wires curved on its working surface in an arc corresponding to the natural curvature of wires passing from coils at one end of the support to coils at its opposite end, a pair of wire holding drums in tandem at each end of the support adapted to pass two parallel wires over said support, means mounting the drums so that each wire passes from the inside drum of one pair to the outside drum of the other pair, whereby the curves of two wires between these respective drums are the same, a cutting tool adjacent to the support engaging the wires traveling over the support, tensioning devices on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving, means for driving said drums and automatic means laterally shifting said drums to maintain the wires parallel on the support. 45
7. In mechanism of the class described, a support for the passage of parallel wires curved on its working surface in an arc corresponding to the natural curvature of wires passing from coils at one end of the support to coils at its opposite end, a pair of wire holding drums in tandem at each end of the support adapted to pass two parallel wires over said support, a cutting tool adjacent to the support engaging the wires traveling over the support, tensioning devices on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving, means for driving said drums and automatic means laterally shifting said drums to maintain the wires parallel on the support. 50
6. In mechanism of the class described, a support for the passage of parallel wires curved on its working surface in an arc corresponding to the natural curvature of wires passing from coils at one end of the support to coils at its opposite end, a pair of wire holding drums in tandem at each end of the support adapted to pass two parallel wires over said support, a cutting tool adjacent to the support engaging the wires traveling over the support, tensioning devices on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving, means for driving said drums and automatic means laterally shifting said drums to maintain the wires parallel on the support. 55
5. In mechanism of the class described, a support for the passage of parallel wires curved on its working surface in an arc corresponding to the natural curvature of wires passing from coils at one end of the support to coils at its opposite end, a pair of wire holding drums in tandem at each end of the support adapted to pass two parallel wires over said support, a cutting tool adjacent to the support engaging the wires traveling over the support, tensioning devices on the side of the cutting tool from which the wires are delivered adapted to engage said plurality of wires placed side by side and passing in engagement with the tool to sufficiently tension said wires passing the tool so that the single tool may simultaneously cut from each wire a steel wool shaving, means for driving said drums and automatic means laterally shifting said drums to maintain the wires parallel on the support. 60
- In witness whereof, I have hereunto subscribed my name.
- ARTHUR J. ROTH.
